(57) **CLAIM**

The ornamental design for a watch dial, as shown and described.

DESCRIPTION

The sole view is a front elevation of a watch dial showing the new design.

The hands that are shown in broken lines and the portions of the watch dial that are bound by broken lines do not form part of the claimed design. The patterns shown by broken lines on the watch dial and the underlying segments on which they are located do not form part of the claimed design.

The claimed portion of the front of the watch dial is flat.
